UNITED STATES PATENT OFFICE

JAY F. WARREN, OF DETROIT, MICHIGAN, ASSIGNOR TO ROBERT T. ROMINE, OF MOUNT CLEMENS, MICHIGAN

PORTABLE STACK LIFTER

Application filed June 16, 1927. Serial No. 199,355.

This invention relates to a portable stack lifter or crane which is capable of being propelled through relatively low doorways or where restricted overhead room is provided. 5 The apparatus is adapted to be moved or carried into or out of a freight car and to straddle a stack of metal of great weight and lift it bodily, as a unit, from the car floor and deposit it on the floor of a truck or other conveyance or vice versa. Such stack lifter or crane is substantially like that shown and described in co-pending applications of Robert T. Romine, Serial No. 133,374 filed September 3, 1926, and Serial No. 171,976 filed 15 March 2, 1927. This application is an improvement in part over the invention shown and described in the aforesaid co-pending applications.

An object of the present invention is to provide a portable stack lifter having an attachment which is adapted to be detachably connected with the load supporting and lifting members or bars of the stack lifter shown and described in said co-pending application 25 Serial No. 171,976, above referred to, and which is adapted for use at steel mills or the like in connection with the loading of freight cars with sheet metal, particularly although not necessarily, finished sheet steel. The attachment comprising my invention enables a 30 pack or pile of metal sheets positioned flatwise upon a buggy or low truck to be lifted as a whole from the truck and deposited, as a unit, upon the car floor. It will be seen that the improved apparatus enables the elimination of the old and well known method of 35 manually transferring the constituent sheets of the pile from the buggy or low truck to the car floor. In accordance with previous practice, two workmen are required to perform the operation of transferring the metal sheets from the buggy to the floor of the car. The individual sheets are manually handled, and hence this method of stacking the sheets 40 on the car floor requires a great amount of time, and involves a very considerable labor expense.

Another object of the invention is to provide an apparatus capable of being readily attached to the stack lifter hoisting apparatus

and which is constructed so as to be fully flexible to allow its use in connection with the handling of packs or piles of metal sheets of varying dimensions.

In the patent to Romine No. 1,650,540, patented November 22, 1927, a method of shipping sheet metal, with the sheets of the packs on edge, is illustrated. It has been found that steel mills, while utilizing this method together with equipment for handling the 55 packs, desire the use of the equipment for handling sheet metal where some consumers, such as small consumers, may require the metal sheets to be shipped in flat stacked 60 packs. The present invention enables flat 65 bound or unbound stacks to be readily and easily handled by means of the portable stack lifter or crane and loaded in the car without any manual handling of the individual sheets as heretofore, so that the stacks may then be 70 braced or otherwise prepared for shipment. One form of my invention is shown in the accompanying drawings wherein like characters of reference indicate similar parts in the several views. 75

In said drawings:

Fig. 1 is a side elevation of my portable stack lifter or crane with the apparatus of this invention connected therewith, the apparatus being shown supporting a pile or 80 pack of the metal sheets arranged flatwise.

Fig. 2 is an end elevation of the apparatus of Fig. 1.

Fig. 3 is a side elevation on an enlarged scale, of my improved apparatus or attach- 85 ment.

Fig. 4 is an end elevation of the construction shown in Fig. 3.

Before explaining in detail the present invention, and the method or mode of operation 90 embodied therein, it is to be understood that the invention is not limited in its application to the details of construction and arrangement of parts illustrated in the accompanying drawings, since the invention is capable of other embodiments and of being 95 practiced or carried out in various ways. Also, it is to be understood that the phraseology or terminology employed herein is for the purpose of description and not of limi- 100

tation, and it is not intended to limit the invention beyond the terms of the several claims hereto appended or the requirements of the prior art.

6 In Figs. 1 and 2 of the drawings I have shown a portable stack lifter or crane V having an arched frame and spaced pairs of supporting legs 10. The stack lifter is normally supported by means of spring pressed caster wheels 11. The upper frame structure of the 10 stack lifter encloses suitable hoisting mechanism including a motor and winding drums which serve to raise and lower longitudinal lifting bars 12. Cables C are wound about the drums and are connected with the lifting 15 bars through the medium of sheave blocks C¹ so as to raise and lower the bars. The construction of the stack lifter is substantially like those of the aforesaid co-pending applications, and a more detailed description of it herein is thought to be unnecessary.

20 My improved apparatus or attachment comprises a pair of pack engaging and supporting units A each of which is detachably connected with and suspended by a pair of transverse horizontal bars 20. Each of the bars 20 is provided at its opposite ends with hook members or attaching means in the form of substantially U-shaped metal plates 21 each having outwardly and downwardly turned end or hook portions 21^a providing means for detachably engaging the bars 12 of the stack lifter. Each member 21 is rigidly secured upon the bar 20 by means of rivets 25 or the like 22. At the upper edge of the bar and adjacent each end thereof there are provided a plurality of notches 23 for a purpose to be hereinafter described. Mounted upon the bar 20 and adapted to be moved longitudinally thereof are a pair of inverted substantially U-shaped coupling or connecting members 24 enlarged at their ends to provide heads or eye portions 24^a which are provided with apertures or holes 25 to receive a detachable pin or bolt 26 having an integral head 26^a at one end, and a transverse hole or slot 26^b adjacent its opposite end.

25 Each unit A comprises a pair of spaced upright gusset plates 27 which are connected together at their lower ends by means of an angle bar 28. The angle bar is provided with a vertical flange 28^a and a horizontal flange 28^b, the vertical flange being in engagement with the lower outer face of each plate 27 and secured thereto by means of rivets or the like 29 having countersunk heads so as to lie flush with the inner face of the plates to prevent them from becoming sheared off when the unit engages a pile of metal S. The horizontal flange 28^b of opposed units is adapted to be inserted beneath a pile or pack S as best shown in Figs. 2 and 4. The gusset plates 27 are each provided adjacent their upper ends with a slot or aperture 27^a through which is 30 inserted a metal loop or link 30. The links 30

35 permit the units A to be connected with and supported by the coupling members 24 and, as shown in Figs. 3 and 4, the upper ends of the links 30 are positioned between the pairs of eye members 24^a and the bolts 26 inserted to maintain the parts in fixed relation. To prevent the bolts 26 from becoming disengaged from the eye members and links, I provide a pin 31 which is inserted through the transverse hole or slot 26^b formed in each 75 bolt.

40 From the foregoing it will be seen that the units A are adjustable longitudinally of the bars 20 and are maintained in adjusted positions through the medium of the notches 23 which receive the upper ends of the coupling members 24 and maintain them against accidental relative movement with respect to the bars 20. Likewise it will be seen that the units may be disconnected from the bars 20 80 by simply releasing the pins 31 and bolts 26.

45 With my improved attachment, packs or piles of metal of different widths may be readily engaged and lifted or lowered by simply adjusting the units A along the bars 20 85 and inserting the flanges 28^b beneath the lower longitudinal edges of the pile. When it is not desired to use the attachment, it is simply necessary to disengage or unhook the end portions 21^a of the members 21 from the 90 bars 12 of the stack lifter.

50 By providing angle bars 28 of sufficient length, it will be seen that piles or packs of metal of various lengths may be readily engaged and lifted by the attachment. By 100 providing such angles, longitudinal adjustment of the apparatus relative to the stack lifter frame is unnecessary, although it will be understood that the units A and the bars 20 may be moved as a whole along the longitudinal stack lifter bars 12 if desired. 105

55 With the foregoing construction, it will be understood that the units A may be disassembled from the bars 20, the bars 20 removed from engagement with the lifting bars 12 and all of the parts of the apparatus, when not in use, stored in a relatively small space. Likewise the parts may be readily and quickly assembled when it is desired to handle 110 packs or piles of sheet metal stacked flatwise, without the necessity of altering the construction of my standard type portable stack lifter or crane. 115

60 It will be noted that the angle bars 28 are of a length to extend a substantial distance 120 beyond opposite sides of the transverse center 100 (Fig. 3) of the pack. These angles which confine the lower edges of the pack when lifted provide rigid supporting trusses effective to prevent bowing or bending of the 125 pack of sheets at the center thereof, indicated by the line 100 in Fig. 3. This construction therefore maintains the pack flat while being lifted by the stack lifter hoisting mechanism and prevents any danger of the angles 130

28 from becoming disengaged from beneath the pack.

What I claim is:

1. In a portable crane having an arched frame and hoisting mechanism, a pair of spaced horizontal lift bars supported from said mechanism, a load engaging and lifting member suspended at opposite ends from said bars, said member comprising devices adjustable on the bars, a plate pivotally connected to each device and an angle bar secured to the lower edges of the plates and having an inwardly extending flange.
2. In a portable crane having an arched frame and hoisting mechanism, a pair of spaced parallel lift bars supported from said mechanism, a pair of transverse lift bars mounted on said first named bars, a load engaging and lifting member suspended at opposite ends from said transverse bars, said member comprising devices adjustable on the bars, a plate pivotally connected to each device and an angle bar secured to the lower edges of the plates and having an inwardly extending flange.
3. In a portable crane having an arched frame and hoisting mechanism, a pair of spaced horizontal lift bars supported from said mechanism, a load engaging and lifting member suspended at opposite ends from said bars, said member comprising devices adjustable on the bars, a depending plate having a pivotal link connection at the upper end thereof with each device and at the lower end thereof provided with a horizontal angle bar having an inwardly extending horizontal flange.
4. In a portable crane having an arched frame and hoisting mechanism including pairs of depending cable operated sheaves, a horizontal bar connecting each pair of sheaves, a pair of horizontal bars extending transversely between said first named bars and adjustable thereon, depending links adjustable on said transverse bars, a pair of spaced depending plates pivotally connected to a pair of said links, and an angle bar connecting the lower ends of said plates and having an inwardly extending flange engageable beneath the load.
5. In a portable crane having an arched frame and hoisting mechanism including pairs of depending cable operated sheaves, a horizontal bar connecting each pair of sheaves, a pair of horizontal bars extending transversely between said first named bars and supported thereon, a hook device suspended at its opposite upper ends from said transverse bars, comprising gusset plates and an angle bar joining the lower edges of the plates.
6. In a portable crane having an arched frame and hoisting mechanism including pairs of depending cable operated sheaves, a horizontal bar connecting each pair of

sneaves, a pair of horizontal bars extending transversely between said first named bars and supported thereon, and a pair of transversely spaced depending hook devices, each hook device suspended at its upper ends from the pair of transverse bars.

In testimony whereof I affix my signature.

JAY F. WARREN.
